UNITED STATES PATENT OFFICE.

WILHELM BENJAMIN HAAS, OF PARIS, FRANCE.

ATTACHMENT FOR CIGAR-HOLDERS AND PIPE-STEMS.

SPECIFICATION forming part of Letters Patent No. 350,359, dated October 5, 1886.

Application filed June 10, 1886. Serial No. 204,746. (No model. Patented in France December 26, 1885, No. 173,163, and in England March 12, 1886, No. 5^o9.

To all whom it may concern:

Be it known that I, WILHELM BENJAMIN HAAS, a citizen of France, residing at Paris, France, have invented certain new and useful 5 Improvements in Attachments for Cigar-Holders and Pipe-Stems, (for which I have obtained Letters Patent in Great Britain, No. 589, dated March 12, 1886, and in France, No. 173,163, dated December 26, 1885,) of which to the following is a full, clear, and exact specification.

This invention has for its object to provide a novel attachment for cigar-holders, whereby, when the holder is placed upon a table, 15 both the holder and the cigar are prevented from coming in contact with the table. This object I accomplish in the manner and by the means hereinafter described and claimed, reference being made to the accompanying drawings, in which—

Figure 1 is a side elevation of a cigar-holder provided with my invention. Fig. 2 is a transverse sectional view taken on the line $z-z$, Fig. 1.

20 In the drawings, the letter A indicates the supporting attachment, consisting of a ring or annulus, a, adapted to be slipped over the cigar-holder C and to be securely held thereon in any suitable manner. To the forward part 30 of the ring are secured two studs, b b, which diverge outwardly and are placed directly opposite each other, and to the rear portion of the

ring is secured an additional stud, b', these studs constituting feet which provide a triangular base for the holder, all in such manner 35 that when the holder is placed on a table both the mouth-piece of the holder and the lighted end of the cigar are prevented from coming in contact with the surface of the table.

The invention is applicable to pipe-stems as 40 well as to cigar-holders, and when applied to a pipe-stem the pipe-bowl is supported with its mouth upward without danger of falling over.

Having thus described my invention, what 45 I claim is—

1. An attachment for cigar-holders and pipe- 50 stems, consisting of the annulus or ring having attached front and rear feet, substantially as and for the purpose described.

2. A cigar-holder provided with a ring, a, adapted to slip over the holder, and having attached front and rear feet, b b', for holding the mouth-piece and the lighted end of a cigar 55 from contact with a table or other surface on which the holder may be placed, substantially as described.

In testimony whereof I have hereunto set my hand and seal in the presence of two subscribing witnesses.

WILHELM BENJAMIN HAAS. [L. S.]
